UNITED STATES PATENT OFFICE.

LEWIS H. CHURCH, OF WESTFIELD, NEW JERSEY, ASSIGNOR TO THOMAS & BETTS CO., OF ELIZABETH, NEW JERSEY, A CORPORATION OF NEW JERSEY.

PIPE-BENDING TOGL.

Application filed April 9, 1927. Serial No. 182,269.

This invention relates to a pipe bending tool, and it is the principal object to provide a simple and inexpensive pipe bending tool, but one which is strong and durable, yet 5 cheap to manufacture.

Another object of my invention, is to provide a pipe bending tool, which will bend pipe at two different radii, as it is sometimes desirable to put a sharper bend at some portion of the pipe.

My invention will be readily understood by reference to the attached drawing, in which Figure 1 is a substantially full size view of the pipe bending tool, in inverted 15 position with a small section of pipe in the tube.

Figure 2 is a view of Figure 1, without the pipe, looking upon the right of Figure 1.

Figure 3 is a reverse view of Figure 1, but 20 showing the pipe placed in the tool in a position to secure the sharper bend on the pipe.

Figure 4 is a view of Figure 1 without the pipe looking from the left.

The pipe bending tool comprises a body 25 portion 1, having a shank 2, the extremity of which is adapted to receive a handle as by means of the screw threads 3. The shank 2 is hollow or has a hole 4 therethrough, the extremity of the hole at the threaded end of 30 the shank being somewhat smaller in diameter than at the end where the body and shank join, thus forming a shoulder 5, the object of which will be later pointed out.

The body portion 1 has a hole or passage- 35 way 6 extending from end to end. The hole 6 is exposed on one side of the body portion 1 by a slot 7 which has a width sufficient to accommodate the passage of the pipe 14, which is to be bent, into the hole 6. The hole 40 4 merges into the hole 6, and at the junction a rounded portion 10 is provided on which the pipe 14 has a changing fulcrum.

During the bending operation a second ful- 45 crum area 11 is provided adjacent the outer rim 8, which rim is enlarged and supported by the rib 13, to give strength to this portion of the tube. An additional strengthen- 50 ing rib 9 is also provided on the top portion of the tube. The body portion 1 is fur- ther strengthened where the holes 4 and 6 merge, as indicated by the rim 12, and where the rim 12 merges into the shank 2, the outer edge of the opening into the shank hole 4 55 is flared or rounded at 15 to provide a chang- ing fulcrum for the pipe to be bent, by use of

the shank hole 4, to be later referred to. In operation, where the larger radius is desired, the tool as shown in Figure 1, is turned upright and the pipe placed through the slot 7 into the transverse hole 6, and the end 60 which is shown in section in Figure 1, rests on the floor. The tool handle is then moved in the direction of the arrow and the pipe is bent with the curved surface 10 as a fulcrum along the direction of the dotted line 16, until it comes in contact with the curved surface 15, at which time that surface acts as the fulcrum and continues so to act until the bend 65 is completed, and due to the rolling or changing fulcrums the pipe is not kinked.

When it is desired to get a sharper bend than can be obtained by bending the pipe in the manner illustrated in Figure 1, the end 70 of the pipe is inserted into the hole 4. The handle of the tool is then moved in the direction of the arrow Fig. 3, it being understood that the free end of the pipe is held in any desired manner, and the pipe is then bent over the rounded surface 15.

It will be understood that the general con- 75 tour of this tool may be varied without departing from the spirit of the invention, and the scope of the appended claims.

Having thus described my invention, what I claim is:

1. A pipe bending tool comprising: a body having a hollow shank extending therefrom, said shank adapted to have a handle attached thereto, said body having a hole extending from end to end therethrough and a slot in 90 one side of the body exposing the hole and having a width sufficient to receive into the hole, the pipe to be bent, said hole having at least a part of its formed surface curved so as to provide a changing fulcrum, said body at opposite ends of said hole having reinforced rims and strengthening ribs and the hole entrances flared to provide a second curved fulcrum area for the pipe as it is bent.

2. A pipe bending tool comprising: a 100 body and a shank extending therefrom, said shank having means for attaching a handle thereto, said body having a hole extending from end to end therethrough and a slot in one side of the body exposing the hole and 105 having a width sufficient to receive into the hole the pipe to be bent, said shank having a pipe receiving hole therein opening into the first mentioned hole adjacent one end thereof, the end entrances to said first mentioned hole 110

and from said hole into the hole in the shank, being flared to provide a changing fulcrum for the pipe to be bent by use of either hole.

3. A pipe bending tool comprising: a body 5 and a shank extending therefrom, said shank having means for attaching a handle thereto, said body having a hole extending from end to end therethrough and a slot in one side of the body exposing the hole and having a 10 width sufficient to receive into the hole the pipe to be bent, said shank having a pipe receiving hole therein opening into the first mentioned hole adjacent one end thereof, said body at opposite ends of the first mentioned hole having reinforced rims and 15 strengthening ribs, the entrances to said first mentioned hole and from it into the hole in the shank, being flared to provide a changing fulcrum for the pipe to be bent by use of 20 either hole.

4. A pipe bending tool comprising: a body and a shank extending therefrom, said shank having means for attaching a handle thereto, said body having a hole extending from end 25 to end therethrough and a slot in one side of the body exposing the hole and having a width sufficient to receive into the hole the pipe to be bent, said shank having a pipe receiving hole therein opening into the first 30 mentioned hole adjacent one end, said body at opposite ends of the first mentioned hole having reinforced rims and strengthening ribs, the outer edge of the opening into the shank hole being flared to provide a changing 35 fulcrum for the pipe to be bent by use of the shank hole, said flared portion also acting as a second fulcrum when a pipe is bent by use of the first mentioned hole.

5. A tool for making in pipe, bends of two 40 radii comprising: a body and a shank extending therefrom and having means for attaching a handle thereto, means for bending a pipe to one radius consisting of a hole extending from end to end therethrough in the body 45 and a slot in one side of the body exposing the hole and having a width sufficient to receive into the hole the pipe to be bent, means for bending a pipe to another radius, consisting of a hole in the shank to receive the pipe, 50 said shank hole being positioned adjacent

one end of said body hole and the entrance thereto as well as the entrances to the body hole being flared as and for the purpose described.

6. A pipe bending tool comprising: a hollow body having a hollow shank, said shank having means for attaching a handle thereto, said hollow body being adapted to receive and hold a pipe and having at least a part of its surface curved to form a changing bearing for the pipe whereby the pipe may be bent on one radius, said shank having a hole opening into one end of the hollow body and adapted to receive the end of a pipe, said shank hole having a rounded bending edge to 60 engage the pipe whereby the pipe may be bent on a smaller radius than said first mentioned bend.

7. A pipe bending tool comprising: a body portion and a shank extending therefrom, 70 said shank having means for attaching a handle thereto, said body having a hole extending from end to end therethrough and a slot in one side of the body, exposing the hole and having a width sufficient to receive 75 into the hole a pipe to be bent, said shank having a pipe receiving hole therein, opening into the first mentioned hole adjacent one end thereof, said body portion where said holes come together being curved to provide 80 a changing fulcrum for the pipe to be bent in the first mentioned hole, said shank hole opposite said rounded portion, being flared and rounded to provide a second fulcrum for a pipe positioned in the shank hole.

8. A pipe bender for bending pipe on two different radii comprising: a body part having a hole extending from end to end therethrough and a slot opening into the hole whereby the pipe may be passed into the hole through the slot, spaced fulcrum points over which the pipe is bent in said hole, a shank having a bore to receive an end of the pipe, the surfaces at the entrance to said bore forming a fulcrum over which the pipe may be bent and means for attaching to the shank an operating lever.

In testimony whereof, I affix my signature.

LEWIS H. CHURCH.
